UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

ACETYLENE-GAS GENERATOR.

SPECIFICATION forming part of Letters Patent No. 635,351, dated October 24, 1899.

Application filed February 25, 1899. Serial No. 706,806. (No model.)

To all whom it may concern:

Be it known that I, FRANK RHIND, a citizen of the United States, residing at Bridgeport, Connecticut, have invented a new and useful Improvement in Acetylene-Gas Generators, of which the following is a specification.

My invention relates particularly to generators of portable size or to those in which it is desirable to cut off the generation of gas before the exhaustion of the supply of carbid and to renew such generation without delay or inconvenience.

In the accompanying drawings, which represent so much of a portable gas-lamp of the cycle type as is necessary to show my invention, Figures I, III, and V are top plan views, and Figs. II, IV, and VI vertical sections, of various forms of my device.

1 designates a liquid-containing chamber or fount provided with depressions 12; 2, a wick-tube; 3, a feed-adjusting device provided with shaft 31 and handle 32; 30, Fig. VI, a different form of feed-adjusting device; 4, a disk pierced at 41; 5, a generating-chamber; 6, a carbid-holder pierced at 61 62 and grooved at 63; 7, a rotating stud having shaft 71 and handle 72, and 8 a partition.

In the example of my invention illustrated in Figs. I and II of the drawings the fount 1 may be of any desired form. The wick-tube 2 is eccentrically placed and, as shown, contains a vertically-adjustable carrier inclosing a wick, which may be of sponge, linen, or any suitable absorptive material. A wick-adjusting pinion, 3 is mounted on an inclined shaft 31, which passes through the wall of the fount and has an exterior handle or button 32. The disk 4 rests on the top of the fount 1 and is secured against rotation, so that its aperture 41 registers with the wick-tube 2. Within the generating-chamber 5 is a carbid-holder 6, shown as a low cylinder whose bottom conforms to the disk 4 and is pierced with a plurality of apertures 61, shown as three, corresponding in radial distance with the aperture 41. A central polygonal aperture 62, preferably reinforced by a washer, as shown, engages upon a correspondingly-shaped stud 7, forming the upper end of a vertical shaft 71, 50 which passes axially through the fount 1 and is provided with a lever-handle 72 at the bot-

tom of the fount. Depressions 12 in the lower edge of the fount 1 engage with the lever 72. Vertical grooves in the wall of the holder 6 seat the extremities of a partition 8, shown 55 as tripartite.

The operation of my device will be readily understood from an inspection of the drawings. When the parts are assembled, as shown in the drawings, the fount 1 being first filled 60 with water and the holder 6 with carbid it is clear that the wick may be raised by means of the button 32 through the aperture 41 in the disk 4 and one of the apertures 61 in the bottom of the carbid-holder 6 and into contact with the carbid. When it is desired to extinguish the flame of the lamp, the wick is lowered and the holder 6 rotated by means of the handle 72, preferably about sixty degrees, so as to bring the aperture 61 out of 70 register with the aperture 41 in the disk 4. The disk then acts as a closure to the bottom of the holder 6 to prevent ascent of vapor from the fount to the carbid. A further rotation of the holder 6 brings the lever 72 into 75 one of the depressions 12 and a second aperture 61 over the wick-tube. The raising of the wick now acts to attack the carbid at a fresh point where there is no cake or a thinner cake of residual lime to be first moistened. 80 Hence the generation of gas begins as soon or nearly as soon as at the first using. As shown, a third aperture in the holder 6 permits a repetition of such extinguishing and relighting of the flame. To insure an immediate generation of gas upon a second or later using, I may provide a vertical partition 8, 85 tripartite or otherwise to correspond with the number of apertures 61 and adapted to set midway of such apertures. This acts to confine the action of the water to a particular portion or pocket of the carbid. I preferably make this partition 8 removable and support it in position by means of grooves 63 in the wall of the holder 6 or in any convenient manner. It is obvious that whether or not the partition 8 is used a bag or piece of cloth may be used within the holder 6 to contain the carbid and facilitate removing of the waste matter.

In Figs. III and IV of the drawings I have shown the fount 1 as inclosed in a case adapted

to be tightly attached to the generating-chamber 5, the fount itself being rotatable by means of a hollow shaft 71, passing through a suitable stuffing-box in the bottom of the fount and provided with an exterior lever-handle 72. The wick-tube 2 is shown as cut away to admit the teeth of a horizontal pinion 3, whose shaft 31 passes through the shaft 71 and is exteriorly provided with a button 32. The wick-carrier in the tube 2 has an inclined rack, so that it is raised and lowered spirally by the pinion 3. The stud 7 is omitted. The carbid-holder 6 is, as illustrated above, pierced with a plurality of apertures 15 to receive the wick. It is clear that as before the holder 6 may when the wick is lowered from its operative position be turned to expose a new portion of the carbid to the action of the water.

20 In Figs. V and VI the carbid-holder and fount are relatively stationary. The wick-tube 2 is offset at its upper end and rotatable by means of a shaft 71, passing through the bottom of the fount and having a lever 72, as 25 already shown. A sleeve surrounding the tube 2 forms a series of inclined recesses or cams 30, with which a laterally-projecting pin on the tube engages to raise and lower the wick during its rotation. It will therefore 30 be seen that the turning of the lever 72 acts both to adjust the wick vertically and to present it successively to the various apertures 61 of the holder 6.

I do not hold my invention limited to the 35 use of the particular gas-generating substances named and still less to the proportions or forms shown or described.

What I claim is—

1. In an acetylene-generator in combination a liquid chamber or fount, a carbid-holder 40 above said fount, means for feeding a liquid from said fount to said holder and means for the relative rotation of one of said parts in a horizontal plane whereby the flow of liquid 45 may be directed successively to various points in said holder, substantially as described.

2. In an acetylene-generator in combination a liquid chamber or fount, a carbid-holder above said fount, manually-adjustable means 50 for feeding a liquid from said fount to said holder and means for the relative rotation of one of said parts in a horizontal plane whereby the flow of liquid may be directed successively to various points in said holder, substantially 55 as described.

3. In an acetylene-generator in combination a liquid chamber or fount, a carbid-holder above said fount, means for feeding liquid from said fount to said holder, a vertical shaft 60 connected to one of said parts and passing out through the bottom of said generator and means as a lever or handle exterior to said generator whereby through the rotation of said shaft one of said parts may be rotated in 65 a horizontal plane whereby the flow of liquid may be directed successively to various points in said holder, substantially as described.

4. In an acetylene-generator in combination a liquid chamber or fount, a carbid-holder above said fount, a body of absorptive material adapted to convey a liquid to said holder and means for the relative rotation of one of said parts whereby the flow of liquid may be directed successively to various points in said holder, substantially as described. 70

5. In an acetylene-generator in combination a liquid chamber or fount, a carbid-holder, a manually-adjustable body of absorptive material adapted to convey a liquid to said holder and means for the relative rotation of one of said parts whereby the flow of liquid may be directed successively to various points in said holder, substantially as described. 75

6. In an acetylene-generator in combination a liquid chamber or fount, a carbid-holder, means as a body of absorptive material for feeding a liquid upward to the carbid in said holder and manually-operative means for the relative rotation of one of said parts whereby the flow of liquid may be presented successively to various points in said holder, substantially as described. 85

7. In an acetylene-generator in combination a liquid chamber or fount, a carbid-holder above said fount, a vertically-adjustable wick 95 in said fount and means for the relative rotation of one of said parts whereby the flow of liquid may be presented successively to various points in said holder, substantially as described. 100

8. In an acetylene-generator in combination a liquid chamber or fount, a carbid-holder above said fount, means for conveying a liquid from said fount to said holder and a vertical shaft passing through said fount and connected with said holder whereby said holder may be rotated in a horizontal plane, whereby the flow of liquid may be directed successively to various points in said holder, substantially as described. 105

9. In an acetylene-generator in combination a liquid chamber or fount, a generating-chamber above said fount, a carbid-holder in said generating-chamber, means as a body of absorptive material for conveying a liquid 115 from said fount to said holder and a shaft passing through said fount and adapted to rotate said holder so as to present the flow of liquid successively to various points in said holder, said holder being detachable from said shaft and removable from said generating-chamber, substantially as described. 120

10. In an acetylene-generator in combination a liquid chamber or fount, a carbid-holder above said fount, a plurality of eccentric apertures in the bottom of said holder, an eccentrically-placed wick-tube in said fount, a shaft passing axially through said fount and engaging with said holder and a handle or lever exterior to said fount whereby said holder 125 may be rotated to present its bottom apertures successively above said wick-tube, substantially as described. 130

11. In an acetylene-generator in combina-

tion a liquid chamber or fount, a carbid-holder above said fount, a plurality of eccentric apertures in the bottom of said holder, an eccentrically-placed wick-tube in said fount, a shaft passing axially through said fount and engaging with said holder, a handle or lever exterior to said fount whereby said holder may be rotated to present its bottom apertures successively above said wick-tube and a non-rotary disk beneath said holder, substantially as described.

12. In an acetylene-generator in combination a liquid chamber or fount, a carbid-holder above said fount, a plurality of eccentric apertures in the bottom of said holder, an eccentrically-placed wick-tube in said fount, a shaft passing axially through said fount and engaging with said holder, a handle or lever exterior to said fount whereby said holder may be rotated to present its bottom apertures successively above said wick-tube and a removable non-rotary disk beneath said holder, substantially as described.

13. In an acetylene-generator in combination a liquid chamber or fount, a horizontally-disposed carbid-holder above said fount, means for conveying a liquid from said fount to said holder, means for rotating one of said parts relatively to the others in a horizontal plane and a partition in said holder, substantially as described. 25

14. In an acetylene-generator in combination a liquid chamber or fount, a carbid-holder above said fount, a plurality of apertures in the bottom of said fount, a body of absorptive material adapted to convey a liquid from said fount to said holder, means for the relative rotation of one of said parts and a partition in said holder dividing it into parts or pockets corresponding in number to said bottom ap- 30 35 40

eratures, substantially as described.
